WEB CONTROLLING MECHANISM

Application filed December 14, 1929. Serial No. 414,121.

The present invention relates to web controlling mechanism and more particularly to such a mechanism for use in connection with high-speed rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is an end elevation of one embodiment of a web controlling mechanism illustrative of the present invention;

Fig. 2 is a vertical section taken on the line 2—2 of Fig. 1;

Fig. 3 is a fragmentary detailed section taken on the line 3—3 of Fig. 1; and

Fig. 4 is a fragmentary detailed section taken on the line 4—4 of Fig. 2.

The present invention has for its object the provision of a web controlling mechanism for maintaining the tension of the web, as it is drawn from the web roll and fed to a printing press or other web using machine, substantially constant under normal operating conditions and for quickly stopping the rotation of the web roll in case the press is stopped or the web breaks, thereby preventing the unrolling of large quantities of the web which would foul the press. The present invention also provides a simple, rugged and sensitive mechanism for controlling the tension of the web and maintaining the tension substantially constant, at the same time permitting the web rolls to be easily replenished.

According to the present embodiment of the invention, means are provided for rotatably supporting a web roll, from which a web of paper is drawn off and led to a web

using machine, such as a rotary printing press, and the web roll supporting means is preferably movable enabling the web roll to be engaged while it is supported on the truck on which it is brought to the web roll supporting mechanism and to be raised therefrom into running position. The tensioning means, coacting with the web roll to tension the web drawn therefrom, preferably comprises a plurality of spaced-apart, flexible, friction belts engaging the periphery of the web roll and pressed into contact therewith to oppose the rotation of the web roll and produce the necessary tension on the web, and for maintaining these flexible friction belts in contact with the periphery of the web roll, there is preferably provided a periodically released weight which moves the belts as the web roll wears down, the action of the weight being controlled by a pilot roller which is moved by the tension of the web in passing from the web roll to the printing press. In order to diminish the frequency of operation of the weight, and to maintain the pressure between the friction belts and the web roll sufficient to produce the constant web tension desired, and for continuously and minutely controlling the pressure between the belts and the web roll, the pilot roller is preferably provided with means for moving the belts independently of the weight. Means are also provided for greatly increasing the pressure between the belts and the web roll for quickly stopping rotation of the web roll when the web breaks or the press is shut down, and as embodied, the pilot roller releases the weight permitting its entire force to be applied to the friction belts.

Other features of the invention will be initially pointed out in connection with the following detailed descriptions of the present preferred embodiment of the invention, and it will be understood that the foregoing general description and the following detailed description are both exemplary and explanatory, but not restrictive of the invention.

Referring now in detail to the present preferred embodiment, illustrated by way of example in the accompanying drawings, the web roll supporting means preferably com-

prises a pair of angularly movable arms 10 supported on a rotatable shaft 11 and provided with bearings 12 at the upper ends of the arms in which the web roll supporting shaft 13 is rotatably journaled. Means are also preferably provided for raising and lowering the web roll supporting arms 10 to raise the web roll 14 from the truck on which it is brought to the web roll supporting mechanism, and to hold the web roll in raised or running position. As embodied, supporting shaft 11, on which the supporting arms 10 are mounted, is provided at one of its ends with a worm gear segment 15 keyed to the shaft and meshing with a worm 16 rotatably mounted in a bracket 17 supported on the upright side frame 18 of the press, the worm, in turn, being connected with a handle 19 by which it is turned to position the supporting arms 10 and web roll 14. The web roll supporting arms 10 are preferably slidably keyed on their supporting shaft 11, and are held in the desired position thereon by suitable means, such as set 25 screws 20, so that the arms can be spaced apart the necessary distance to accommodate the different widths of web rolls.

Means may, and preferably are, provided for bodily moving the web roll supporting arms, and the web roll supported thereby transversely of the web to register the web with the cylinders of the printing press to which the web is fed, and for this purpose supporting shaft may be provided with a threaded end portion 21 cooperating with a threaded hand wheel 22 held against axial movement. By turning the hand wheel, the shaft 11, arms 10 and web roll 14, can be moved from one side of the supporting structure to the other.

For guiding the web from the web roll to the press, or other web using machine, there are preferably provided guide rollers 23 of suitable construction and positioned so as to guide the web through the desired path.

According to the present invention, the tensioning of the web is preferably effected by means of friction members which are stationary and rub on the periphery of the web roll, thereby exerting a drag on the rotation of the web roll, and creating the necessary tensioning of the web. As embodied, these friction members preferably comprise flexible spaced-apart belts 25, which are pressed into contact with the periphery of the web roll, and under normal operating conditions, are maintained in contact therewith with sufficient pressure to produce a substantially constant web tension, although the pressure is preferably greatly increased as the press is stopped, or the web breaks. In the present embodiment there are provided a plurality of these friction belts 25 securely fastened, at their lower ends, to a bar 26, extending from one side of the web roll sup-

porting mechanism to the other and seated in the lower side reaches 27 of the press frames.

For pressing the friction belts into contact with the periphery of the web roll, and for maintaining them in contact with the periphery of the web roll as the web roll wears down, or gradually diminishes in diameter, the upper ends of the friction belts are fastened to individual rollers 29 mounted on shaft 30 rotatably journaled in the side frames 18 of the press, these rollers being in substantial alignment with the lower ends of the friction belts, and weighted means are provided for winding the belts on the rollers 29 as the web roll wears down to take up the slack in the belts and maintain them in contact with the web roll. Guide roller 32 is preferably provided, over which the belts 25 run, and is substantially in line with the centers of the web roll 14 and the rod 26 to which the lower ends of the belts are fastened, so that the belts can be pressed into contact with even a very small stub of a web roll.

The weighted means for winding the belts on the rollers and for maintaining the belts in contact with the web rolls preferably comprises a relatively large weight 33, sufficient to exert the maximum required pressure between the belts and the surface of the web roll to stop the web roll quickly, and is vertical slidably in a trackway formed between the angled pieces 34 extending vertically along the edges of the upright portion of one side frame 18 of the press. Weight 33 is connected with the rollers 29 for turning the rollers, and preferably a cable 35 is attached to the weight, extends upwardly over pulley 36, and is wound on a pulley 37 at one end of the roller shaft 30, the cable being releasably connected with the pulley by means of a retaining screw 38, as shown in Fig. 4.

Means are preferably provided, in accordance with the present invention for controlling the application of the weight to the belts, and for permitting the weight to move the belts only when the belts become sufficiently slack to exert insufficient pressure on the surface of the web roll, although in accordance with the invention, the controlling means may be so adjusted that the weight will be controlled to exert the necessary and desired pressure between the belts and the web roll and thereby maintain the tension of the web substantially constant. In the embodied form, the means for normally restraining movement of the weight comprises a brake controlling the movement of the roller shaft 30 and permitting the weight 33 to move to take up the belts as they become loose on the surface of the web roll. This brake preferably comprises a brake drum 39 fixed on roller shaft 30 and cooperating with a pair of brake shoes 40, pivotally mounted on brake arms 41, which are pivoted by a common pivot

pin 42 secured to the side frame of the press. The brake shoes are pressed into contact with each other by tie bolt 44, and spring 45, the tension of which can be varied by hand 5 wheel 46.

For minutely and continuously controlling the tension of the web as it is drawn from the web roll and for maintaining the web tension substantially constant under normal conditions of operation, there is preferably provided a pilot roller 48, moved by a loop in the web 49 as it passes to the printing press or other web using machine, and this pilot roller is preferably connected with the friction belts 10 in such a manner as to maintain the tension produced by the pressure between the friction belts and the periphery of the web roll substantially constant. As embodied, the pilot roller 48 is supported by a pair of arms 50 15 pivotally mounted in the upright side frames of the press by means of shaft 51, and at either side of the press frame 18, the arms 50 being held fixed on the shaft by means of keys 52. At their upper ends, arms 50 are 20 provided with slots 53 adapted to receive the ends of the pilot roller shaft 54 and to move arms 50 as the pilot roller moves. Pilot roller 48 is provided with journal blocks 55 in which the ends of shaft 54 are journalled, and these blocks are slidably mounted in horizontal slideways 56 at either side of the press frame. In passing to the press, the web 49 is looped over the pilot roller 48 between the 25 guide rollers 23, the tension of the web moving the pilot roller against the tension of springs 58 at one end of each of the side-ways. These springs 58 are preferably of sufficient length so that their tension changes very slowly as they are compressed. For 30 connecting the pilot roller 48 with the friction belts 25, there is provided rollers 59 mounted on shaft 60 extending from one arm 50 to the other and rotatably journalled on the shaft 60. The friction belts 25 are 35 looped over these rollers 59 as they pass from guide roller 32 to the rollers 29 on which they are wound. As the pilot roller moves, rollers 59 are subjected to a corresponding movement and increase or decrease the pressure 40 between the belts and the surface of the web roll. In case of a stopping of the press, or a break in the web, the pilot roller quickly moves to the right (of Figure 1) at the same time greatly increasing the pressure between the belts and the web roll and stopping the 45 rotation of the web roll.

Means are also provided for controlling the action of the brake 39, 40 on the weight 33 and permitting the weight to take up slack in the friction belts, and for this purpose the pilot roller is connected with the brake, and permits the weight to act when the pilot roller 48 has been drawn to a definite position by the tension of the web. In the normal 50 operation of the tension controlling mecha-

nism, the pilot roller acts continuously to control the tension of the belts, and the weight acts periodically to take up the slack in the belts and to move the pilot roller to the left, and thereby the weight maintains the 70 belts in contact with the web roll, while the pilot roller controls the tension of the web. Between the brake arms 41, and serving to open them and release the brake is an operating cam 64, pivotally mounted on pin 65 and provided with an operating lever 66 connected with the cam. As the cam is moved from its normal position, as shown, it spreads the 75 brake shoes and allows the weight to descend tightening the belts and simultaneously moving the pilot roller to the left (Figure 1). Operating cam 64 is preferably connected with the pilot roller by means of a link 67 pivotally connected at one end to the upper end of lever 66, and at its other end connected with the arms 50 by means of a slot and pin connection 68 so that movement of the pilot roller beyond a predetermined limit will cause a corresponding movement of the brake operating cam. The slot and pin connection serves to reduce the frequency of 80 operation of the weight on the friction belts 25, and prevents excessive wear of the brake shoes, at the same time assisting in maintaining the tension of the web more nearly constant.

As shown in the drawings, the present embodiment of the invention when the web breaks, or when the press is stopped, the pilot roller 48 will move to the extreme right hand position (Figure 1) opening the brake shoes 40 and applying the full force of weight 33 to the friction belts 25, and at the same time the belt tensioning roller will be moved to the right also tending to press the belts into firmer contact with the surface of the web rolls, and this combined action on the belts will create a very large pressure between the belts and the web roll, quickly stopping the rotation of the web roll.

Under certain operating conditions, it will be found desirable to retard the action of the weight in moving the belts, and permitting to be applied thereto only gradually as the brake shoes are released. For this purpose the weight may be provided with a dashpot or other suitable retarding device to cause the weight to act slowly on the belts and move the pilot roller to the left without undue tension upon the web. This will increase the frequency of operation of the weight, but will make the tension somewhat more constant than would otherwise be the case.

For enabling the mechanism to be operated by a single operator with very little effort, means are provided for facilitating the lifting of the weight 33 to its uppermost position, as is necessary when a new web roll is to be put into running position, and for this purpose, there is provided a rack 69 vertically

extending within one of the angle-pieces 34 attached to the side frame and forming the trackway for the weight, and cooperating with this rack is a small pinion 70 rotatably mounted in the body of the weight, and fast on shaft 71, by which it is rotatably mounted. At its outer end, shaft 71 is provided with a squared-end 72 onto which a crank may be fitted for easily turning the pinion and lifting the weight 33, thereby loosening the friction belts.

The invention in its broader aspects is not limited to the specific mechanism shown and described but departures may be made therefrom within the scope of the accompanying claims without departing from the principles of the invention and without sacrificing its chief advantages.

What I claim is:

1. Web controlling mechanism including in combination, a web roll support, friction belts engaging the surface of the web roll, weighted means to move the belts to maintain them in contact with the periphery of the web roll and means for periodically rendering the weighted means operative.

2. Web controlling mechanism including in combination, a web roll support, friction belts engaging the surface of the web roll, a weight to press the belts against the web roll surface, means for normally preventing the weight from acting on the belts, and means controlled by the tension of the web for controlling the movement of the belts by the weight.

3. Web controlling mechanism including in combination, a web roll support, friction belts engaging the surface of the web roll, a weight for pressing the belts against the web roll surface, a brake normally preventing movement of the weight, a pilot roller moved by the tension of the web, and means connecting the brake and pilot roller for releasing the brake and allowing the weight to maintain the belts in contact with the web roll as the web roll wears down.

4. Web controlling mechanism including in combination, a web roll support, friction belts engaging the surface of the web roll, a weight connected with the friction belts, a pilot roller moved by the tension of the web and controlling the movement of the weight for maintaining the web tension substantially constant, said pilot roller being movable independently of said weight.

5. Web controlling mechanism including in combination, a web roll support, friction belts engaging the surface of the web roll, a weight periodically operative on the friction belts, a pilot roller moved by the tension of the web, means connecting the pilot roller and the weight for controlling the periodic operation of the weight by a predetermined movement of the pilot roller and means for controlling the periodic operation of the

weight by a predetermined movement of the pilot roller.

6. Web controlling mechanism including in combination, a web roll support, friction belts engaging the surface of the web roll, a weight periodically operative on the friction belts for maintaining the belts in contact with the periphery of the web roll, and a pilot roller moved by changes in the tension of the web and means for controlling the periodic operation of the weight by a predetermined movement of the pilot roller for maintaining the tension of the web substantially constant.

7. Web controlling mechanism including in combination, a web roll support, friction belts engaging the surface of the web roll, a weight connected to one end of the belts for pressing the belts into contact with the periphery of the web roll, and a pilot roller connected with said belts intermediate their ends and moved by the tension of the web for varying the pressure between the belts and the web roll.

8. Web controlling mechanism including in combination, a web roll support, friction belts engaging the surface of the web roll, a weight connected with the belts for moving the belts to maintain them in contact with the periphery of the web roll, a pilot roller connected with the belts for moving the belts to control the tension of the web drawn from the web roll, means normally holding the weight against movement, and means controlled by the pilot roller for permitting the weight to move the belts.

9. Web controlling mechanism including in combination, a web roll support, friction belts engaging the surface of the web roll, a weight for moving the belts, a pilot roller for moving the belts, a brake normally holding the weight against movement, and means controlled by the pilot roller for releasing the brake whereby the belts are maintained in contact with the periphery of the web roller.

10. Web controlling mechanism including in combination, a web roll support, friction belts engaging the surface of the web roll, a weight for periodically moving the belts to maintain them in contact with the web roll, a pilot roller operable independently of said weight, moved by the tension of the web and connected with the belts and means for controlling the periodic operation of the weight by a predetermined movement of the pilot roller for maintaining the tension substantially constant.

11. Web controlling mechanism including in combination, a web roll support, friction belts engaging the surface of the web roll, a weight for periodically moving the belts to maintain them in contact with the web roll, a pilot roller moved by the tension of the web and connected with the belts and

- means for controlling the periodic operation of the weight by a predetermined movement of the pilot roller for moving the belts to maintain the pressure between them and the web roll to produce a constant web tension as the web roll wears down, said pilot roller being operable independently of the weight. 5
12. Web controlling mechanism including in combination, a web roll support, friction belts engaging the surface of the web roll, a weight connected with the belts, means for periodically releasing the weight to press the belts into contact with the web roll and for stopping the web roll when the web breaks. 10
13. Web controlling mechanism including in combination, a web roll support, friction belts engaging the surface of the web roll, a weight connected with the belts, a pilot roller connected with the belts and means controlled by the pilot roller for periodically releasing the weights to maintain the belts in contact with the periphery of the web roll and for pressing the belts against the web roll when the web breaks to stop the web roll. 15
14. Web controlling mechanism including in combination, a web roll support, friction belts engaging the surface of the web roll, a weight connected with the belts, a pilot roller connected with the belts, means normally holding the weight against movement, and means connecting the pilot roller and weight for releasing the weight on relatively large reductions in web tension. 20
15. Web controlling mechanism including in combination, a web roll support, friction belts engaging the surface of the web roll, a pilot roller for moving the belts on small changes in web tension, a weight controlled by the pilot roller for moving the belts on large reductions in web tension, the pilot roller and weight coacting to stop the web roll when the web breaks or the web using machine is stopped. 25
16. Web controlling mechanism including in combination, means for rotatably supporting a web roll, friction belts engaging the surface of the web roll for tensioning the web, weighted means for maintaining the belts in contact with the web roll, and means for periodically releasing the weighted means and allowing it to move the belts into contact with the web roll. 30
17. Web controlling mechanism including in combination, a web roll support, friction belts engaging the surface of the web roll, a weight periodically operative on the friction belts for maintaining the belts in contact with the periphery of the web roll, a pilot roller connected with the belts and moved by changes in the tension of the web and means for controlling the periodic operation of the weight by predetermined movement 35
- of the pilot roller for maintaining the tension of the web substantially constant, said pilot roller being movable independently of said weight. 70
- In testimony whereof, I have signed my name to this specification. 73
